(57) **CLAIM**

The ornamental design for set of rectangular stackable serving plates, as shown and described.

DESCRIPTION

FIG. 1 is a top perspective view of set of rectangular stackable serving plates, showing the front, top and left sides, in a stacked configuration;

FIG. 2 is a left side view thereof;

FIG. 3 is a left side cross-section view thereof taken from line 3-3 on FIG. 1;

FIG. 4 is a perspective view thereof, showing the bottom, left and front sides;

FIG. 5 is a perspective view thereof, showing the top, left and front sides, with the set of rectangular stackable serving plates in a separated configuration;

FIG. 6 is a left side view thereof, with the set of rectangular stackable serving plates in a separated configuration; and,

FIG. 7 is a perspective view thereof, showing the bottom, left and front sides, with the set of rectangular stackable serving plates in a separated configuration.
